UNITED STATES PATENT OFFICE

MAURICE KNUPFFER, OF LONDON, ENGLAND

LIQUID-FUEL BURNER

Application filed August 7, 1930, Serial No. 473,615; and in Great Britain May 16, 1929.

The present invention relates to improvements in and relating to liquid and gaseous fuel burners, and is particularly applicable to burners burning the less volatile distilled oils such as Diesel and domestic oils, although residue oils can be burned smokelessly if rather repeated cleaning of the burner is tolerated.

The present invention provides a burner in which the fuel is substantially completely consumed with the production of an incandescent flame, and carbonization is prevented or minimized.

To this end a burner according to the present invention comprises in combination a combustion chamber having a high hot wall, a double bottom serving to conduct preheated primary air, and a vaporizing chamber or groove located within the double bottom, the said double bottom and the said vaporizing chamber or groove being in efficient heat conducting relationship with the high hot wall, means for supplying the fuel to such vaporizing chamber or groove, means for directing the heated air into or over such chamber or groove, a spreader or the like to conduct and direct the hot gases or flames towards the high hot wall and means for introducing a secondary air supply centrally into the combustion zone. The secondary or additional supply of air may be cold air.

Conveniently and advantageously the oil vaporizing chamber may be in the form of an open-topped groove; but an annular chamber provided with discharge jets may be employed if desired.

For starting the burner, any suitable subsidiary heater effective for the purpose of vaporizing the oil may be used.

The burner may be worked on natural or forced draught, and any suitable controls may be incorporated for adjusting the air supply, adjusting or cutting off the oil supply, and adjusting or cutting off the subsidiary heater.

In an exemplary form of the present invention the oil vaporizing chamber or groove is arranged at the inner ends of ribs or webs which extend outwards to connect the outer wall of the oil chamber to the bottom of the combustion chamber and to bridge this and

the base of the burner to form the pre-heating primary air conducting passages. In a circular type of burner these passages may be so arranged as to impart a known whirling movement to the air. The passages for the secondary colder air may be so arranged as to impart a contrary motion thereto.

In order that the present invention may be the more readily understood, reference is hereinafter made to the constructional examples thereunder which are illustrated in the accompanying drawings, in which:

Fig. 1 is a sectional elevation of a circular type of burner embodying the present invention and as adapted to work by natural draught.

Fig. 2 is a half plan view of Fig. 1 with the spreader 16 and the refractory liner 23 of the combustion chamber removed.

Fig. 3 is a sectional elevation of a modification of the device shown in Fig. 1.

Fig. 4 is a sectional view of means for preventing or minimizing air draught fluctuations.

Figs. 5 and 6 are half plan and vertical sectional views of a modified type of burner adapted to burn either gas or oil, the spreader and the refractory liner being omitted from Figure 5.

Fig. 7 shows how the burner may be lowered and swung clear of the boiler, furnace or like for cleaning, inspection, etc., purposes and Fig. 8 is a detail view of Fig. 7.

Referring to Figs. 1 and 2 of the accompanying drawings; a circular type of burner under the present invention is illustrated which consists of a metallic cylindrical pot-like casing 1, having a double bottom 2, 3 bridged by an arcuate series of inclined ribs or webs 4 which with openings 5 in the casing 1 form primary air conducting passages leading over the vaporizing groove or chamber to the combustion chamber 6.

The base proper 3 of the casing 1 is provided with an open-topped circular groove 7 surrounding a central opening 8. The inner wall 9 of the groove 7 rises conveniently in frusto conical form above the outer wall 10 which may be oppositely sloped. Over the inner wall 9 is fitted a corresponding shaped

cap 11 having a foot flange 12 and radial ribs 13. The cap 11 is connected to a perforated shallower conical plate 14 to which a shouldered support 15 for a mushroom-like flame spreader of refractory material 16 is fixed by passing it through a hole in the plate 14 and screwing it into a cross member 17. This cross member bridges the opening 8. The shouldered support is locked to the plate 14 by tightening the lock nut 18.

The centrally situated perforated plate 14 serves for the introduction of secondary air which is colder than the primary air to assist combustion. By this arrangement the air is delivered where it is most needed for this purpose, and as it does not pass near the surface of the vaporizing groove or chamber it does not retard vaporization. Moreover as it is delivered into the combustion zone immediately below the lower surface of the flame spreader it materially decreases the amount of carbonization thereon.

19 is a flange by which the burner is supported in the furnace, boiler or like, and below this and adjacent to the primary air inlets 5, a subsidiary or starting heater is arranged, which in the example illustrated is a gas ring 20 having its jets 21 opposite to and directed towards the openings 5.

30 Liquid fuel is delivered under appropriate control to the groove 7 by the pipe 22.

23 designates a refractory lining of the combustion chamber bottom 2 and the inside of the rising wall thereof.

35 It is an essential feature of this apparatus that there should be efficient heat conduction from the walls to the double bottom and the vaporizing groove or chamber, thereby to ensure effective heating of the air and vaporization of the fuel. In order to increase the supply of heat available for this purpose I prefer to carry the walls a substantial distance above the edge of the spreader as shown in Fig. 1.

45 The desired temperature of the oil groove will of course vary according to the particular oil used, and this temperature can be raised or lowered in designing the burner by varying the height of the walls or the number or/and thickness of the webs or ribs 4, or by lifting or lowering the mushroom-like spreader 16.

50 The temperature of the burning gases in the combustion chamber can be controlled by varying the area of the secondary air inlet.

55 For starting the burner, it is important to heat the burner sufficiently to vaporize the oil as soon as this is admitted. This pre-heating can be variously effected.

60 As soon as the heavy oil begins to burn, it is economical to cut off the subsidiary heater and this can be appropriately arranged to be done by manual or automatic means as found most convenient.

65 A burner according to the present inven-

tion can be adjusted to work at a very small draught e. g. 0.1" water gauge.

As the burner is usually working on natural draught it becomes important to adjust the draught in the first instance to the right amount by an ordinary damper. The prevent an excessive draught or fluctuations thereof, an automatic damper regulator as shown in Fig. 4 may be installed in the flue. The weight 37 keeps the flap plate 38 closed as long as the draught does not exceed a predetermined pressure say 0.1" w. g. This can be varied by adjusting the screw 39. If the draught increases, additional air is admitted to the flue through the opening 40 by the flap 38 being lifted, and in this way will maintain a constant draught on the burner.

As shown in Fig. 3 the mushroom 16 may be hollow with a tubular stand 17 through which additional or secondary air is blown. In the top part of the mushroom holes 41 are drilled in such a way as to rotate the gases in an upwardly direction, thereby inducing more air through the burner. Or more air may be supplied by induced draught in the flue.

The burner is provided with proper safeguards for its working, but these forming no part of the present invention are not described herein.

Burners under this invention may be embodied as combustion apparatus of all kinds of furnaces, kilns, boilers, etc.

A burner is illustrated in Figures 5 and 6 suited for burning either gas or oil, and also adapted when used for burning oil to be pre-heated by gas, without resorting to a separate gas ring.

This burner is similar to that previously described with reference to Figs. 1 and 2, except that the burner head 47 is provided with a circular series of jets 48 to which gas is delivered by the pipe 49 by way of the annular chamber 50 on the one hand, and oil is delivered by way of the same annular chamber by the oil pipe 51 on the other.

The burner head is given a conical formation down which the heavier constituents of the oil may flow over the bottom plate 3 where they are completely vaporized. Any deposits of asphalt will tend to collect at the base of the conical surface where they will lie in the stream of the primary air and be eventually burnt away as the temperature within the burner increases.

The central portion 52 of the burner head is surrounded with an air-space 52a to retard the transfer of heat from the bottom plate of the burner.

The burner head comprises a removable ring 53 to facilitate cleaning of the chamber 50 and jets 48.

In this construction of burner the aim is to get the oil into the burner so cold as to obviate carbonization in the inserted part and

particularly in the jets, while at the same time the bottom plate of the burner should be made so hot as to evaporate not only the heavy constituents of the oil but also the asphalt content thereof.

5 Figs. 7 and 8 show how burners under the present invention may be adapted to be lowered and swung clear of the boiler 54 or the like. For this purpose the burner support 10 55 is provided with a radial extension 56 having a tubular end 57 to rotatably fit over a sleeve 58 fitting loosely round a screw 59 upstanding from the base of the boiler, said sleeve 58 having at the foot thereof two flanges 60, 61 forming between them an annular recess 62 which loosely receives a ring member 63 secured to a lever arm or nut 64 so that by rotating the nut the burner may be raised or lowered. When lowered the 15 burner is free to be turned to the dotted line position indicated in Fig. 7.

If desired a perforated mantle 65 of appropriate material may be mounted over the burner as shown in Fig. 7.

25 What I claim is:—

1. Liquid fuel burner comprising in combination a combustion chamber having a high wall adapted to become hot when the burner is operated, a double bottom extending from said wall and through which double bottom primary air is passed and heated in its passage therethrough, a vaporizing chamber located within the double bottom, the said double bottom and the said vaporizing chamber being in efficient heat conducting connection with the high wall so that the vaporization of the fuel is aided by the heat conducted from the said wall, means for supplying the fuel to such vaporizing chamber, means for directing the heated air to the fuel vaporized in said chamber, a spreader to conduct and direct the burning gases towards the high wall, and means for introducing a secondary air supply centrally into the combustion zone.

2. Liquid fuel burner comprising in combination a combustion chamber having a high wall adapted to become hot when the burner is operated, a double bottom extending from said wall and through which double bottom primary air is passed and heated in its passage therethrough, a vaporizing chamber located within the double bottom, the said double bottom and the said vaporizing chamber being in efficient heat conducting connection with the high wall so that the vaporization of the fuel is aided by the heat conducted from the said wall, means for supplying the fuel to such vaporizing chamber, means for directing the heated air to the fuel vaporized in said chamber, a hollow spreader to conduct and direct the burning gases towards the high wall, and means for introducing a secondary air supply into said hollow spreader.

3. Liquid fuel burner comprising in combination a combustion chamber having a high wall adapted to become hot when the burner is operated, a double bottom extending from said wall and through which double bottom primary air is passed and heated in its passage therethrough, a vaporizing chamber located within the double bottom, the said double bottom and the said vaporizing chamber being in efficient heat conducting connection with the high wall so that the vaporization of the fuel is aided by the heat conducted from the said wall, means for supplying the fuel to such vaporizing chamber, ribs bridging said double bottom for directing the heated air to the fuel vaporized in said chamber, a spreader to conduct and direct the burning gases towards the high wall, and means for introducing a secondary air supply centrally into the combustion zone.

4. Liquid fuel burner comprising in combination a combustion chamber having a high wall adapted to become hot when the burner is operated, a double bottom extending from said wall and through which double bottom primary air is passed and heated in its passage therethrough, a vaporizing chamber located within the double bottom, the inner wall of said vaporizing chamber being frusto conical, a removable cap fitting thereover, the said double bottom and the said vaporizing chamber being in efficient heat conducting connection with the high wall so that the vaporization of the fuel is aided by the heat conducted from the said wall, means for supplying the fuel to such vaporizing chamber, means for directing the heated air to the fuel vaporized in said chamber, a spreader carried by said removable cap, said spreader conducting and directing the burning gases towards the high wall, and means for introducing a secondary air supply centrally into the combustion zone.

5. Liquid and gaseous fuel burner comprising in combination a combustion chamber having a high wall adapted to become hot when the burner is operated, a double bottom extending from said wall and through which double bottom primary air is passed and heated in its passage therethrough, a vaporizing chamber located within the double bottom, the said double bottom and the said vaporizing chamber being in sufficient heat conducting connection with the high wall so that the vaporization of the fuel is aided by the heat conducted from the said wall, a jet fitting isolated from the base of the burner proper for supplying the fuel to such vaporizing chamber, means for directing the heated air to the fuel vaporized in said chamber, a spreader to conduct and direct the burning gases towards the high wall, and means for introducing a secondary air supply centrally into the combustion zone.

6. Liquid fuel burner comprising in combination a combustion chamber having a high wall adapted to become hot when the burner is operated, a double bottom extending from 5 said wall and through which double bottom primary air is passed and heated in its passage therethrough, a vaporizing chamber located within the double bottom, the said double bottom and the said vaporizing chamber 10 being in efficient heat conducting connection with the high wall so that the vaporization of the fuel is aided by the heat conducted from the said hot wall, means for supplying the fuel to such vaporizing chamber, 15 means for directing the heated air to the fuel vaporized in said chamber, a spreader to conduct and direct the burning gases towards the high wall, a starting heater, and means for introducing a secondary air supply 20 centrally into the combustion zone.

7. Liquid fuel burner comprising in combination a combustion chamber having a high wall adapted to become hot when the burner is operated, a double bottom extending 25 from said wall and through which double bottom primary air is passed and heated in its passage therethrough, a vaporizing chamber located within the double bottom, the said double bottom and the said vaporizing chamber 30 being in efficient heat conducting connection with the high wall so that the vaporization of the fuel is aided by the heat conducted from the said wall, means for supplying the fuel to such vaporizing chamber, 35 means for directing the heated air to the fuel vaporized in said chamber, a spreader to conduct and direct the burning gases towards the high wall, means for introducing a secondary air supply centrally into the combustion 40 zone, and means for adjusting the position of the burner.

8. Liquid fuel burner comprising in combination a combustion chamber having a high wall adapted to become hot when the 45 burner is operated, a double bottom extending from said wall and through which double bottom primary air is passed and heated in its passage therethrough, a vaporizing chamber located within the double bottom, the said 50 double bottom and the said vaporizing chamber being in efficient heat conducting connection with the hot wall so that the vaporization of the fuel is aided by the heat conducted from the said wall, means for supplying the fuel to such vaporizing chamber, 55 means for directing the heated air to the fuel vaporized in said chamber, a spreader to conduct and direct the burning gases towards the high wall, means for introducing a 60 secondary air supply centrally into the combustion zone, a flue in communication with the combustion chamber, and draught regulating means in the flue.

In testimony whereof, I affix my signature.

MAURICE KNUPFFER.
